PUMP

Matthew W Huber, Chicago, Ill., assignor to Hydraulic Controls, Inc., a corporation of Illinois

Application December 2, 1942, Serial No. 467,629

3 Claims. (Cl. 74—60)

This invention relates to high pressure positive displacement pumps in which the cylinders are arranged in circular series around the drive shaft and the plungers are actuated by a swash plate (or other cam) mounted on said shaft.

The pump is an improvement on that described in my copending application, Serial No. 462,563, filed October 19, 1942. That pump operates successfully at nearly 4400 R. P. M. against head pressures of 1500 pounds per square inch, and has the important characteristic of being indifferent to the direction of rotation of the drive shaft.

Where unidirectional rotation of the drive shaft is feasible, the present invention permits modification of the prior pump so as to operate at higher speeds or against higher pressures or both.

The invention assures a more direct thrust reaction of the swash plate or cam upon the pump plungers by skewing the cylinder bores, so that the axis of each bore is tangent to a quick pitch helix concentric with the shaft axis instead of being parallel with the shaft axis. This disposition of the cylinders is such with reference to the cam angle that at mid stroke on the displacement stroke of each plunger the axis of the cylinder is nearly normal to the thrust face of the cam. Thus the lateral thrust component of the cam on the plunger is reduced, as is the total axial thrust. This consideration is important because anything which will reduce bearing loads in a high pressure pump of this type has a marked beneficial effect. The described arrangement is practicable because the displacement thrust on the plungers is unidirectional. It gives a decided directional characteristic to the pump, so that it is considered undesirable to permit the shaft to turn backward when the pump is under load.

A modification of the pump illustrated in the prior application to incorporate the present invention, is illustrated in the accompanying drawing in which:

Fig. 1 is an approximately axial section of the complete pump.

Fig. 2 is a side elevation of the pump shown in Fig. 1 with a portion broken away to show one cylinder in section so that its inclination may be seen.

Fig. 3 is a section on line 3—3 of Fig. 1.

Fig. 4 is an end elevation of the cylinder block.

Fig. 5 is a perspective view of the swash plate.

Statements of direction in the following spe-

cification assume that the pump is positioned as in Fig. 1. The direction of rotation of the shaft is indicated by an arrow placed on the shaft in Fig. 1.

5 The pump is lubricated by the hydraulic liquid which it pumps, normally an oil of reasonably good lubricating properties.

The main shell or housing of the pump is preferably composed of a strong aluminum alloy, and is divided transversely into two components 11 and 12 having mating flanges 13 and 14. The flange 13 is somewhat the thicker of the two and the two flanges are connected by machine screws 15 (see Fig. 3). These pass through the flange 14 and are threaded into the flange 13. The two holes indicated at 16 in Fig. 1 pass through both flanges and are intended to receive bolts which hold the pump against its mount (not shown).

20 The cylinder block 17 is cylindrical in form and has an axial bore to receive the bearing bushing hereinafter described. It also has a peripheral flange 18 which seats in a circular rabbet deeper than the flange and formed at the mating area of the flanges 13 and 14. The flange 18 is sealed by a gasket 19 which fills the remaining space in the rabbet to the right of the flange 18. This gasket is initially of circular cross section. The arrangement is such that 25 the right hand end of the cylinder block is subject to pump discharge pressure so that the cylinder block is urged strongly to the left against the seat formed in the portion 12 of the pump housing to receive flange 18.

30 A circular series of cylinder bores, eight of which are shown, are formed in the cylinder block. The axes of these bores may be considered as tangent to similar imaginary uniformly spaced quick-pitch helices generated around the 35 axis of the pump shaft. The pitch of the imaginary helices can be estimated by an examination of Fig. 2. The cylinder block is of steel and suitably heat-treated.

35 Each cylinder bore receives a pump plunger 45 21 and the inclination of the bore and plunger is such that the axis of each plunger is nearly but not quite normal to the engaged surface of the actuating cam, hereinafter described, when the cam has moved the plunger to its mid stroke position in a displacing direction. This 50 is the position shown in Fig. 2.

The plungers 21 are axially bored as indicated at 22 in Fig. 1 and have radiating lubricating passages 23 which lead to circumferential grooves 55 24 cut in each plunger. This is the lubricating

arrangement used in the structure of the earlier application. The grooves are so spaced that their traces overlap as the plungers reciprocate.

There are also two cross bores 25 which are exposed when the plunger reaches its limiting position to the left. The cross bores thus serve as inlet ports. The open position is shown as to the lowermost plunger in Fig. 1. The cross bores also assist in the lubrication of the plungers. The plungers are of steel and are suitably heat treated.

An automatic discharge valve of the disc type is provided for each cylinder bore, the valve seating against the end face of the cylinder block 17. There is one valve 26 for each cylinder, each valve being cup-shaped and seated by a coil compression spring 27. Vents 28 (see Fig. 1) prevent liquid from being trapped behind the valves around the springs 27.

Each plunger has an enlarged head 29 on its outer end. A coil compression spring 31 encircles the outer end of the plunger behind the head and reacts between the head and the cylinder block to urge the plunger outward, i. e. to force it on its suction stroke. Each head 29 is provided with a spherical socket whose depth exceeds its radius. Ball-like thrust heads 32 are pressed into these sockets and when pressed to place tilt freely and are retained because of the constricted entrance opening. Each such ball has a flat thrust face formed on a protruding boss which acts to limit the tilting motion of the ball to a little more than that necessary for the operation of the pump.

The cylinder block 17 is positioned in the housings 11 and 12 by means of a stake, not visible in the drawing, but of ordinary form. The stake engages the head portion of the housing 11. The cylinder block is so closely clamped that the stake need perform little more than an initial positioning function. The space between the head of the housing 11 and the cylinder block 17 is the discharge space of the pump and communicates with a groove 34 (see Fig. 2) cut in the periphery of the cylinder block and so located as to lead to the discharge port 35.

The pump shaft turns in a bearing bushing 37 which is pressed into the axial bore of the cylinder block 17 and thus is fixed therein. This bushing makes a close fit with an aligned bore of the inner face of the head of body 11 and produces a seal therewith by sealing ring 38 received in a rabbet formed in the inner end of the bearing bushing. An oil groove 33 extends the entire length of the bushing 37 and supplies oil for lubrication at pump inlet pressure. Gasket 38 prevents leakage from the discharge pressure chamber to the interior of the bearing bushing. Both the gaskets 19 and 38 are preferably formed of an oil resisting rubber substitute.

The drive shaft 39 carries an actuating cam, here indicated as a swash plate 41, which has a hub 42 which is keyed at 50 to the drive shaft 39. The shaft 39 turns in the bushing 37 and the hub 42 turns in a bushing 43 which has a flange 44 seating against the housing section 12 and serving as a thrust bearing for the swash plate. Various disc cams could be substituted for the swash plate, which is a special type of cam.

The shaft 39 is driven by a driving disc 45 which has a flattened hub 46 received within a cross slot at the end of the shaft and retained therein by the machine screw 47.

In the example illustrated, the oil to be pumped enters the housing 12 through radial slots 48 75

which are formed both in the body and in the hub of the swash plate (see Fig. 5). The purpose in this arrangement is to ensure ample lubrication of the rotating hub and swash plate. Other arrangements to admit oil to the interior of the housing 12 are possible.

It is preferred to insert a floating annular disc 49 between the inclined face of the swash plate and the thrust heads 32. This plate rotates at a speed slower than that of the swash plate and serves to distribute wear. As suggested in the earlier application, a series of superposed discs can be used but the one shown is ordinarily sufficient. The use of such plates is not possible with disc cams having other than plane thrust surfaces.

The operation of the pump is not changed materially by duplicating these floating discs, though the wear is distributed because the motion between the contacting parts is somewhat reduced.

The use of the discs is a part of the subject matter claimed in the earlier application and is not broadly claimed herein. The operating characteristics of the present pump are similar to those of the pump of the earlier application, but the present pump has the advantage that at mid-stroke in the displacing direction, the plungers are more nearly normal to the thrust surface which actuates them. On the return stroke, they are at an exaggerated and hence unfavorable angle with the thrust surface, but at that time this surface is retreating and the thrust load is at a minimum.

With this arrangement of the plungers, the pump is capable of sustained operation at somewhat higher speeds and at somewhat higher pressures than those permissible with the pump of the prior application. There is, however, the limitation that the pump should be driven in only one direction. Where this requirement can be met, the arrangement is desirable.

Generally stated, the design is worked on a basis such that the thrust of the swash plate on the plunger, and the lateral frictional drag which it exerts on the plunger, produce at mid-stroke a thrust which is practically coincident with the axis of the plunger. Thus the design is affected in some degree by the intended speed of operation and the intended head pressure, each of which enters as a factor in determining the degree of lateral frictional drag.

The invention can be applied with various disc cams. The particular types of discharge valve and ball thrust head, though preferred, are subject to variation. The same applies to details of the bearings and similar components.

The illustrated embodiment above described in detail is therefore to be taken as merely one possible embodiment of the general inventive principle.

What is claimed is:

1. The combination of a rotary shaft; a disc cam turning therewith; means forming a plurality of cylinders arranged in a circular series around said shaft, the axes of the cylinders being tangent to similar quick pitch helices surrounding said shaft; plungers in said cylinders; and means urging said plungers toward said cam, the pitch of said helices being such that the plungers are approximately normal to the surface of the cam at mid length of their displacing strokes.

2. The combination of a rotary shaft; a swash plate turning therewith; means forming a plurality of cylinders arranged in a circular series around said shaft, the axes of the cylinders being

tangent to similar quick pitch helices surrounding said shaft; plungers in said cylinders; a floating thrust plate interposed between the ends of said plungers and said swash plate; and means urging said plungers toward the swash plate, the pitch of said helices being such that the plungers are approximately normal to the surface of said swash plate at mid length of their displacing strokes.

3. The combination of a rotary shaft; a disc 10 cam turning therewith; means forming a plurality of cylinders arranged in a circular series

around said shaft, the axes of the cylinders being tangent to similar quick pitch helices surrounding said shaft; plungers in said cylinders; and means urging said plungers toward said cam, the pitch of said helices being such that the combined effect of thrust and frictional drag on the plunger heads produces resultant forces approximately aligned with the axes of the plungers through the mid-ranges of their displacing strokes.
